UNITED STATES PATENT OFFICE.

MARTIN C. NEUNER, OF LOS ANGELES, CALIFORNIA.

REINFORCED-PAPER-MAKING MACHINE.

967,958.

Specification of Letters Patent. Patented Aug. 23, 1910.

Application filed October 7, 1908. Serial No. 456,652.

To all whom it may concern:

Be it known that I, MARTIN C. NEUNER, a citizen of the United States, residing at Los Angeles, in the county of Los Angeles 5 and State of California, have invented a new and useful Reinforced-Paper-Making Machine, of which the following is a specification.

This invention relates to a machine for 10 producing reinforced paper, such, for example, as the paper shown in a previous patent of mine No. 879,573, issued February 18, 1908.

The reinforced paper, which it is the object of the present machine to produce, consists of a paper the pulp of which may be composed of any of the well known materials, and a reinforcing material which is incorporated in the pulp of the paper in 20 such a manner that the fiber or pulp penetrate the interstices of the reinforcing material.

The reinforcing material consists preferably of a fabric having a comparatively 25 coarse mesh, the threads of which are composed of an absorbent material so that the pulp not only penetrates between the threads of the fabric but also is absorbed by and penetrates the threads themselves, thereby 30 producing a paper which is much stronger than paper of the ordinary kind consisting of pulp only. The reinforcing material may extend through the whole area of the sheet of paper, or it may consist of a strip which is 35 located at the particular place in the paper where the paper is to be subjected to greatest wear or strain.

I am aware that heretofore fabrics have been sized by coating with a material to 40 render them opaque or give them a surface which can be written upon, such, for example, as window shades or tracing linen, but the paper produced by the present machine is essentially different from such 45 fabrics in that the main body of the paper consists of paper pulp and the fabric which is employed as a reinforcement is inserted in the pulp while the pulp is in plastic form and spread out as a sheet so that the amount 50 of pulp which forms the thickness of the leaf is not dependent upon the reinforcing fabric for the reason that the requisite amount of pulp is first spread out and then the fabric is placed in the pulp. This makes 55 it possible to produce any of the various

thicknesses and grades of papers as heretofore and to impart to them the same finish as heretofore. The threads of the reinforcing fabric being absorbent and soft not only readily absorb the pulp so as to make a 60 perfect union therewith but owing to their softness also readily flatten out as the paper passes through the finishing operation performed by the rolls, cylinders and other devices. 65

The main object of the invention is to make it possible to produce any of the various grades and types of paper heretofore produced and to not change the quality of the material of which such papers are produced but to add the reinforcement to such papers without changing their appearance. 70

While the invention in its combination includes means for producing and forming a layer of pulp into which the reinforcing 75 fabric is to be inserted and also includes means for finishing the paper, such pulp forming means and finishing means may be of any preferred form, such, for example, as a Fourdrinier machine. The means for 80 placing the reinforcement in the pulp comprises a device which I have so constructed and designed that it may be applied directly to a paper making machine, such, for example, as the Fourdrinier machine, 85 without changing or altering the structure of the machine or the altering or interfering in any way with the normal operation of the machine or formation and treatment of the pulp. 90

A further object is to enable the device to be readily attached to machines of various widths and to provide means for accurately adjusting the device so that either a sheet or a strip of reinforcing material will be 95 placed in exactly the desired position relatively to the width of the paper or at the required point between the two surfaces of the paper.

Referring to the drawings:—Figure 1 is 100 a longitudinal vertical sectional view taken through the “wet end” of the machine, the paper making machine forming part of the combination comprising a machine of the Fourdrinier type. The section is taken on the line x^1-x^1 Fig. 2. Fig. 2 is a plan view of the apparatus shown in Fig. 1, such features of the paper making machine as are irrelevant to an understanding of the invention not being shown. This figure shows the 110

apparatus for introducing a strip of reinforcing material. Fig. 3 is an enlarged plan view similar to Fig. 2 showing the apparatus as employed for inserting a sheet of reinforcing material which substantially fills the same area as the paper. Fig. 4 is a side elevation of the attachment, part of the bracket for supporting the idle reel being broken away. Fig. 5 is a rear elevation of the attachment with part of the supporting tube broken away. Fig. 6 is a section on line x^6-x^6 Fig. 4. Fig. 7 is a section on line x^7-x^7 Fig. 4. Fig. 8 is an enlarged side elevation of the feeding wheel and adjacent parts, the paper pulp, screen, and rolls being in section. Fig. 9 is a plan view on a reduced scale of the feeding roll designed for placing a strip of reinforcement in the paper, the width of reinforcement being shown by dotted lines. Fig. 10 is a perspective view of a portion of a sheet of paper reinforced with a strip of reinforcement, a part of the pulp being broken away to reveal the reinforcing strip. Fig. 11 is a side elevation of the remainder of the paper making machine. Fig. 12 is a section on line $x^{12}-x^{12}$ Fig. 4.

Referring to Figs. 1 and 2, the main part of the machine shown consists of the "wet end" of a Fourdrinier machine. 1 designates the wire cloth, 2 the deckle straps and 3 the side bars of the deckle frame which frame, as is well known, is so supported that when the machine operates the frame receives a shaking motion. As the various parts of this portion of the machine are well known, a more detailed description is unnecessary.

The attachment, shown in position in Figs. 1 and 2 and in detail in Figs. 4 to 7 inclusive, comprises a feeding wheel or cylinder 4 having a crowned face and mounted to rotate on a sleeve 5 which is supported by a bolt 6 in the lower end of two vertical frame bars 7. A plate 8 is secured to one side of the wheel 4 and is provided with teeth 9 which are adapted to engage with the reinforcing fabric and prevent slippage of the fabric. The bars 7 are attached to two frame plates 10 by bolts 10' which engage in slots 11 in the plates 10 and thus permit the bars 7 to be raised or lowered and thereby afford adjustment of the feeding wheel 4 to the desired elevation.

A guide finger 12 is supported horizontally slightly below and in front of the feeding wheel 4, by a curved bracket 13 which is pivoted to the bolt 6 and has a lug 14, as shown in Figs. 4 and 6, through which two thumb screws 15 project. The thumb screws bear against the edge of one of the bars 7 and afford means for adjusting the guide finger 12 forward and back, and for varying its elevation with respect to the wheel 4. For example, by loosening the upper thumb

screw 15 and screwing in the lower thumb screw 15, the finger 12 will be retracted and lowered slightly, while by loosening the upper thumb screw and screwing in the lower thumb screw, the finger 12 will be moved forward and elevated slightly as the bracket 13 pivots on the bolt 6.

The plates 10 are fastened together by four bolts 16. Each plate 10 has two rivets, the heads of which project beyond the inner face of the plate 10 to receive reel bars 18, 19. Each reel bar has a slot 20 in its lower end, and an intermediate slot 21 which communicates with a hole 22, the latter being large enough to slip over the head of the upper rivet 17 to permit the reel bar to be slipped down so that the shanks of the rivets 17 engage in slots 20, 21, and thus detachably hold the reel bars in place on plates 10. Riveted to the upper end of the reel bar 18 is a spring bar 23 which has a notch 24 to receive the axle 25 of the reel 26. Two rollers 27 are carried by the spring bar 23 and press against the hub 28 of the reel, their pressure being produced by the inward spring of the spring bar 23, the upper end of reel bar 18 being tapered as shown to permit inward movement of spring bar 23. A thumb screw 29 passes through the spring bar 23 and bears against the reel bar 18 and affords means for regulating the pressure of the rolls 27 against the reel. This device acts to prevent accidental rotation of the reel and keeps it from running under its own momentum. The upper end of the reel bar 19 is also notched to receive the other end of the axle 25 and a handle 30 is provided on the axle to enable the reel to be readily lifted out of its support. A pair of arms 31 are riveted to the plates 10 and as clearly shown in Fig. 1 extend rearwardly and have notched ends 32 for receiving the axle 25 to support a reel which is not in use.

Two sleeves 33 are arranged in the lower part of the plates 10, the outer ends of the sleeves being flush with the outer faces of the plates 10. Extending through each sleeve 33 is a supporting tube 34 and each supporting tube 34 is connected detachably with a similar supporting tube 35 by means of an internal sleeve 36, as clearly shown in Fig. 7, it being preferred to secure the tube 34 irremovably to the tube 35 and to permit of the tube 35 being slipped off from the end of sleeve 36 when necessary. In Fig. 5 the tube 35 has been removed. The two supporting tubes 34 are secured to one side of the deckle frame 3 as shown in Fig. 1 by blocks 37, while the two supporting tubes 35 are secured by similar blocks 37 to the other side of the deckle frame. The tubes 34 extend through the sleeves 33. One of the sleeves 33 is grooved in its upper wall to receive a rack 38 which has a ring 39 at

one end encircling the tube 34, and a thumb screw 40 serves to adjustably secure the rack 38 to the tube 34. Journaled in the plate 10 is a shaft 41 having a worm 42 which engages rack 38 and a milled thumb piece 43 enables the worm to be easily turned. It is obvious that by loosening the thumb screws 40 that plates 10 and all parts carried thereby may be shifted longitudinally 10 on the supporting tubes 34, 35, in either direction and thereby cause the reinforcing material to be fed to the pulp at the desired point with respect to the width of the sheet of paper to be produced. After the 15 approximate position has been secured by sliding the reel the thumb screw 40 is tightened and then by manipulating the worm 42, a most accurate adjustment of the device can be secured.

20 As shown in Fig. 1 the reinforcement feeder is located over the wire cloth and it is preferred to place it as near the end roll of the wire cloth as is convenient so that the reinforcement will be fed into the pulp immediately after the fresh pulp has been 25 spread on the wire cloth and while the pulp is in its most liquid condition.

44 designates the reinforcement material, which is wound on the reel 26. By referring 30 to Fig. 8 it will be seen that the feeding wheel 4 is so adjusted that a portion of its rim revolves in the pulp and it is preferred to adjust the finger 12 at a point slightly below the perimeter of the wheel 4. 35 The reinforcing material passes from the reel 26, thence between a pair of guide rollers 45 shown in Fig. 1, thence over the wheel 4 which drives the reinforcement into the pulp, the reinforcement strip 44 being 40 caused by the finger 12 to gradually sink, so that as the reinforcement leaves the finger 12 it lies about in the middle of the pulp. Obviously if it is desired to have the reinforcement lie near the upper face 45 of the paper, the finger 12 should be adjusted at a higher elevation than shown, while if the reinforcement is to occupy a position closer to the other face of the paper, the finger 12 should be adjusted to a 50 lower elevation.

As the sheet of pulp passes along the reinforcement is drawn into the pulp in a continuous manner, the forward portion of the reinforcement having a sufficiently secure 55 anchorage in the pulp to unreel the reinforcement and draw it into the pulp as the reel turns very freely, and is only retarded sufficiently to prevent the reel from running faster under its own impetus than the reinforcement is reeled off. Thus the reinforcement after having once been inserted in the pulp is not displaced therein nor does it draw or distort the position of the fibers in the pulp, and during the passage of the 60 reinforcement from the feeding wheel 65

through the remainder of the machine, the fresh pulp becomes thoroughly intermingled with the mesh of the reinforcement and the reinforcement in turn becomes softened by the wet pulp and absorbs the same and thus the reinforcement is perfectly incorporated with the pulp. During the progress of the reinforcement through the pulp on the deckle frame the feeding apparatus being mounted on the deckle frame also partakes of the shaking motion so that the feeding wheel 4 and the reinforcement are always maintained in exact position between the two deckle straps 2 and thus the pulp does not become agitated by the reinforcement as there is no sidewise movement of the reinforcement relatively to the pulp.

The presence of the reinforcement displaces that slight amount of pulp which is not absorbed by the threads, although a considerable portion is absorbed and the soft threads of the reinforcement become flattened out during their progress through the press rolls *k*, drying cylinders, and calenders and do not produce any bulging of the paper after it is finished.

The pulp with the reinforcement incorporated therein after passing from the deckle frame travels through the first press rolls *k*, 95 second press rolls *L*, drying cylinders *M* and calenders *O* the remainder of the machine shown in Fig. 11, and the paper is finished in the well known manner.

Fig. 3 shows the reinforcement introducing device constructed substantially the full width of the deckle frame. In this form all of the parts are as previously described except that those parts which extend laterally are made of greater length to span the width of the deckle frame and to accommodate the wide sheet of reinforcement. The width of the device is a trifle less than the space between the side bars 3 of the deckle frame which permits the device to 105 be adjusted the necessary amount on tubes 34 and 35. The clamp 39, rack 38 and worm 42 are located at one end of the device near one of the sides of the deckle frame as clearly shown. This width of device is used 110 when the reinforcing fabric is to extend through the entire width of the sheet of paper.

What I claim is:

1. Means for producing a sheet of paper 120 pulp, means for supporting a roll of reinforcing material adjacent the sheet of pulp, means for guiding the reinforcing material into the pulp at a point substantially midway of the thickness of the pulp, and means 125 for regulating the supporting means and the guiding means laterally with respect to the pulp.

2. Means for producing a sheet of paper 130 pulp, means for supporting a roll of rein-

forcing material adjacent the sheet of pulp, means for guiding the reinforcing material into the pulp, and means for regulating the supporting means and the guiding means laterally with respect to the pulp, and means for regulating the guiding means laterally relatively to the supporting means.

3. Means for producing a sheet of paper pulp, means for supporting a roll of reinforcing material adjacent the sheet of pulp; means for guiding the reinforcing material into the pulp at a point substantially midway of the thickness of the pulp, and means for regulating the guiding means vertically and laterally with respect to the pulp.

4. Means for producing a sheet of paper pulp, means for suspending a guide wheel in said pulp over which wheel a reinforcement material passes, and a guide finger extending transversely of the line of movement of the reinforcement material in said pulp behind said wheel for guiding said reinforcement after it leaves the wheel.

5. Means for producing a sheet of paper pulp, means for suspending a guide wheel in said pulp over which wheel a reinforcement material passes, a guide finger extending transversely of the line of movement of the reinforcing material for guiding said reinforcement after it leaves the wheel, and means for adjusting said finger vertically.

6. In combination with a paper making machine including means for forming paper pulp in a layer, a pair of rods extending transversely over said machine and supported thereby, and means adjustable longitudinally on said rods for guiding and introducing a reinforcement material into said sheet of pulp.

7. In combination with the shaking deckle frame of a paper making machine, a pair of supporting tubes extending across said frame and secured thereto, a reinforcement guiding means mounted slidably on said tubes, and a clamp for clamping said guiding means in various positions on said tubes.

8. In combination with the shaking deckle frame of a paper making machine, a pair of supporting tubes extending across said frame and secured thereto, reinforcement guiding means mounted slidably on said tubes, a clamp for clamping said guiding means in various positions on said tubes, a rack connected with said clamp, and a worm on said guiding means engaging said rack for adjusting the guiding means relatively to the rack and clamp.

9. In combination with a paper making machine, means for guiding a reinforcement into the sheet of pulp produced in said machine, said means comprising a pair of slotted plates supported above said machine, a pair of bars extending below said plates, bolts passing through the slots in

said plates into the bars for holding the bars adjustably in position, and a guide wheel supported by said bars for guiding the reinforcement into the pulp.

10. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, and a guiding finger supported by said bracket for guiding the reinforcement.

11. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, a guide finger supported by said bracket for guiding the reinforcement, a bolt passing through both of said bars, and a spacing sleeve on said bolt between said bars said guide wheel being journaled on said sleeve and said bracket being pivoted on said bolt.

12. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, and a plate having pins in its periphery and secured to the guide wheel.

13. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said

- bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, a guiding finger supported by said bracket for guiding the reinforcement, reel bars extending up from said plates the upper end of the reel bars being notched, a reel, and an axle through the reel adapted to rest in said notched reel bars.
14. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, a guiding finger supported by said bracket for guiding the reinforcement, reel bars extending up from said plates the upper end of the reel bars being notched, a reel, and an axle through the reel adapted to rest in said notched reel bars each of said plates having a pair of inwardly projecting headed studs each of said reel bars having orifices to fit over the heads of said studs and having slots extending from said orifices, said slots being adapted to slide over said studs.
15. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, a guiding finger supported by said bracket for guiding the reinforcement, reel bars extending up from said plates the upper ends of the reel bars being notched, a reel, an axle through the reel adapted to rest in said notched reel bars, and means on one of said reel bars for restraining the rotation of the reel from undue movement.
16. In combination with a paper making machine, means for guiding a reinforcement into the sheet of pulp produced in said machine said means comprising a pair of slotted plates supported above said machine, a pair of bars extending below said plates, bolts passing through the slots in said plates into the bars for holding the bars adjustably in position, a guide wheel supported by said bars for guiding the reinforcement into the pulp, a bracket pivotally supported by said bars, a pair of thumb screws in said bracket and pressing against one of said bars and located on opposite sides of the pivotal point of said bracket for adjusting the position of said bracket, a guiding finger supported by said bracket for guiding the reinforcement, reel bars extending up from said plates the upper end of the reel bars being notched, a reel, an axle through the reel adapted to rest in said notched reel bars the upper end of one of said reel bars comprising a spring bar, a pair of rollers mounted in said spring bar and bearing against the hub of the reel, and a thumb screw through the spring bar bearing against the reel bar the upper end of the reel bar being tapered.
17. In a paper making machine, a deckle frame, rods extending transversely across the deckle frame and bolted thereto, a frame slidably supported on said rods, reel bars extending up from said frame, a reel on said reel bars, for carrying a reinforcement material, and a guide wheel suspended in the pulp by said latter frame for guiding the reinforcement material from the reel into the pulp.
18. Means for producing a sheet of paper pulp including a shaking deckle frame, a pair of tubes adapted to be secured to each side of the deckle frame, a frame for supporting a guide wheel, a guide wheel on the latter frame, and internal sleeves joining the adjacent ends of the respective pairs of tubes permitting one pair of tubes to be interchanged with other pairs of various lengths to accommodate different widths of deckle frames said second frame being slidably mounted on said tubes.
19. Means for producing a sheet of paper pulp including a shaking deckle frame, a pair of tubes adapted to be secured to each side of the deckle frame, a frame for supporting a guide wheel, a guide wheel on the latter frame, internal sleeves joining the adjacent ends of the respective pairs of tubes permitting one pair of tubes to be interchanged with other pairs of various lengths to accommodate different widths of deckle frames said second frame being slidably mounted on said tubes, and means for clamping the second frame to said tubes.
20. Means for producing a sheet of paper pulp including a shaking deckle frame, a pair of tubes adapted to be secured to each

side of the deckle frame, a frame for supporting a guide wheel, a guide wheel on the latter frame, internal sleeves joining the adjacent ends of the respective pairs of tubes permitting one pair of tubes to be interchanged with other pairs of various lengths to accommodate different widths of deckle frames said second named frame being slidably mounted on said tubes, means 5 for clamping the second frame to said tubes, 10

and means for adjusting said second frame relatively to said clamping means.

In testimony whereof, I have hereunto set my hand at Los Angeles, California, this 1st day of October 1908.

MARTIN C. NEUNER.

In presence of—

G. T. HACKLEY,

IRVING J. MITCHELL.
